United States Patent Office

Des. 183,684
Patented Oct. 14, 1958

183,684

SAUCEPAN

Robert O. Ernest, Oak Park, Ill., assignor to Sunbeam Corporation, Chicago, Ill., a corporation of Illinois

Application August 23, 1956, Serial No. 42,711

Term of patent 14 years

(Cl. D81—10)

Fig. 1 is a top perspective view of a saucepan embodying my design;

Fig. 2 is a front elevational view thereof;

Fig. 3 is a bottom perspective view of the saucepan;

Figs. 4 and 5 are side and rear elevational views, respectively, thereof; and

Fig. 6 is a top plan view of the saucepan.

I claim:

The ornamental design for a saucepan, substantially as shown.
